UNITED STATES PATENT OFFICE.

L. D. MOUSER, OF HASTINGS, NEBRASKA.

CLOTHES-LINE STICK OR STRETCHER.

SPECIFICATION forming part of Letters Patent No. 779,284, dated January 3, 1905.

Application filed November 14, 1903. Serial No. 181,258.

To all whom it may concern:

Be it known that I, L. D. Mouser, a citizen of the United States, residing at Hastings, in the county of Adams and State of Nebraska, have invented new and useful Improvements 5 in Clothes-Line Sticks or Stretchers, of which the following is a specification.

My invention relates to improvements in clothes-line sticks and stretchers; and the object of my invention is to provide a clothes-line stick or stretcher by means of which the operator may tighten or loosen one or more clothes-lines readily and conveniently to the desired extent in a manner to be fully described hereinafter.

In the accompanying drawings, Figure 1 is a perspective view of the clothes-line stick or stretcher embodying my invention. Fig. 2 is a detached perspective view of the upper end of 20 the standard and the locking member. Fig. 3 is a detached perspective view of the operating-handle and its coöperating connection. Fig. 4 is a perspective view of the upper end of the standard with its attached parts, the 25 casting 3 shown partly in section.

Referring now to the drawings, 1 indicates a standard of any desired height, the lower end of the standard being suitably journaled or swiveled, as indicated at 2, whereby the 30 standard may be revolved. Connected to the upper end of the standard is a casting 3, having depending flanges, as indicated, which embrace and are suitably connected to the upper end of the standard. Projecting from this 35 casting 3 is a spool or reel 4, having at its upper end a flange 5. Connected with this spool or reel are the wires or lines 6, to which the clothes-lines will be attached in any suitable manner.

40 The standard 1 is rotated through the medium of a suitable cross-handle 7. This cross-handle is swiveled to the standard 1, whereby its end 8 may be vibrated vertically through the medium of a suitable bolt 9. For the purpose 45 of assisting in attaching the handle 7 to the standard and at the same time limiting the amount of vertical movement of the end 8 the handle is provided with a vertically-elongated slot 10, through which a suitable screw 50 or bolt 11 passes. For the purpose of strength-

ening the standard at the point at which the handle 7 is attached I provide blocks 12 and 14, which are attached to opposite sides thereof by securing-bolts, which pass through these blocks and the standard, as shown in dotted 55 lines in Fig. 1.

From the foregoing it will be understood that by rotating the standard 1 through the medium of the handle 7 the wires or lines 6 can be drawn to any desired tension or slackened, whereby the clothes-lines can be conveniently reached for the purpose of hanging the clothes thereon and then the standard 1 rotated for the purpose of tightening the lines to the desired height. 65

For the purpose of locking the standard with the lines 6 at the desired tension or height I provide a locking hook or member 15, which consists of the two arm portions 16 and 17, the arm 16 provided with an inturned end 18 70 and the arm 17 provided with essentially an L-shaped end 19. These ends 18 and 19 are passed through openings 20, which are formed in the flanges of the casting 3, and the bent ends rest upon the shoulders at the upper end 75 of the standard 1. The outer end of this locking member or hook 15 is provided with a suitable hook 21, which is adapted to engage one of the lines 6 when moved up in the position indicated in Fig. 1. For the convenient 80 operation of this locking member 15 I provide a connection 22 in the form of a rod, which has its upper end connected with the locking member 15 at the point 23 and its lower end connected with the end 8 of the 85 handle 7. When the end 8 of the handle 7 is moved upward to the position shown in Fig. 1, the locking member is carried to the position to have its hook 21 engage one of the wires or lines 6, and the standard 1 will then be locked 90 and prevented from rotating and the lines held at the desired tension or height. If the handle is moved downward, the hook will be released from one of the lines, and the standard may then be rotated either for the purpose of tightening or slackening the lines, as 95 may be desired.

From the foregoing description it will be observed that the operator can readily release the tension of the lines 6 through the medium 100

of the handle 7 and at the same time lock the lines at the adjusted tension by simply moving up upon the end 8 of the handle 7.

When the invention is to be used in connection with one clothes-line, one of the lines 6 may be made fast to a post or other object directly opposite the clothes-line, which, together with the clothes-line, will support the standard.

Having thus described my invention, what I claim as new, and desire to secure by Letters Patent, is—

1. A device of the character described, comprising a vertically-arranged rotatable standard adapted to have attached thereto a line, a movable locking member carried by the standard and adapted to engage the said line, means for rotating the standard, and a connection between the said means and the said locking member, substantially as described.

2. A device of the character described, comprising a vertically-arranged standard adapted to have a line attached thereto and wrapped therearound, a laterally-extending vertically-movable locking member carried by the said standard, a laterally-arranged vertically-movable handle connected to the standard and by means of which it may be rotated, and a connection between the vertically-movable handle and the vertically-movable locking member, whereby the standard may be rotated by the handle and the locking member controlled thereby, substantially as described.

3. A device of the character described, comprising a vertically-arranged rotatable standard, a spool projecting from its upper-end and adapted to receive a line, a laterally-arranged vertically-movable locking member having its inner end pivotally connected with the standard, a laterally-arranged handle connected

with standard and by means of which it may be rotated, and a depending member connected with the locking device, whereby the locking device may be moved vertically for engaging and disengaging said line, substantially as described.

4. A device of the character described, comprising a vertically-arranged rotatable standard, a casting embracing its upper end, the casting having an upwardly-projecting spool adapted to receive a line, a laterally-extending locking member having its inner end pivotally seated in the casting, the outer end of the locking member extending upward and adapted to engage the said line, a laterally-arranged handle connected to the standard, and by means of which it may be rotated, the said handle supported to have a vertical movement, and a connection between the handle and the locking member, whereby the handle performs the double function of rotating the standard and of controlling the locking member, substantially as described.

5. A device of the character described, comprising a vertically-arranged rotatable standard adapted to have attached thereto a line, a member connected with the standard and adapted to rotate it, and a lock controlled by the said member and adapted to engage and disengage the said line, substantially as described.

In testimony whereof I have hereunto set my hand in the presence of two subscribing witnesses.

his
L. D. X MOUSER.
